UNITED STATES PATENT OFFICE.

ALTHEA MILLER, OF NEW YORK, N. Y.

CALENDAR.

1,270,431.

Specification of Letters Patent. Patented June 25, 1918.

Application filed August 4, 1916. Serial No. 113,067.

To all whom it may concern:

Be it known that I, ALTHEA MILLER, a citizen of Newfoundland, and a resident of the city of New York, borough of Manhattan, in the county of New York and State of New York, have invented certain new and useful Improvements in Calendars, of which the following is a specification.

The object of this invention is to provide a convenient reminder of the current month-day and week-day by means of a device which may be associated with a watch-cover or other convenient support. A further object is to provide this device in a structure having few parts and in which the month-day and week-day may be displayed in relatively large characters.

In the accompanying sheet of drawings which forms a part of this application,

20 Figure 1 is a view of the back of a watch, the cover of which carries a device embodying my invention;

25 Fig. 2 is an edge view of the watch, the back cover and calendar disks being in section;

Fig. 3 is a view of the month-day disk;

Fig. 4 is a view of the week-day disk;

Fig. 5 is a view of a modified form of month-day disk; and

30 Fig. 6 is a view of a modified form of week-day disk.

The device embodying my invention is shown associated with the back cover *a* of a watch. A month-day disk *b* carries on its periphery digits arranged in such sequence and in such spacing that they may be associated in pairs or taken singly so as to represent any one of the thirty-one days of the month. This disk may be of celluloid, alu-

35 minum, or any other suitable material, and as shown it may be reinforced at the center by a disk *c* of fine light colored silk, linen or muslin, and may be properly backed to prevent scratching. The disk is carried by

40 a spindle *d* upon which it is suitably and removably mounted, and this spindle is journaled in the cover and has a milled head *e*.

45 Concentric with the month-day disk and superimposed thereon is a week-day disk *f* loosely mounted on the spindle, but having sufficient friction therewith to prevent undesired rotation in respect thereto. This disk bears the names of the days of the week as ordinarily abbreviated, and is provided with

50 55 teeth *g g* on its periphery.

In the cover is an opening *h* through which

the name of a week-day may be seen, and an opening *k* which is just wide enough for two associated digits and no more forming the designation of a month-day to be seen. This 60 opening also affords access to the teeth of the week-day disk to permit the latter to be set by inserting the point of a pin.

Two arrangements of digits for representing the days of the month are shown. In 65 Fig. 3 is shown an arrangement for setting to successive days by right-hand or clockwise rotation of the spindle knob except for three transpositions, where it is necessary to turn back for 12 after 11, for 14 after 13, 70 and for 23 after 22. If all the 31 days of the month were separately provided for on the disk, then with the necessary spacing each digit could be given an angular space on the disk amounting to one-sixty-second 75 part of the periphery. But it will be seen that by the rearranging shown each digit can occupy one-forty-eighth part of the periphery, and can therefore be proportionately larger. This gain in the main results 80 from the elimination of separate digits for representing the month-days from 1 to 9 inclusive, and suitably inserting spaces after the numerals 21 to 29 inclusive so that digits 1 to 9 inclusive which are associated with 85 these numerals may be displayed singly through the opening in the cover. Further gain results from having a digit 1 associated with the numeral 12 to provide for the numeral 11, in having a digit 2 associated with 90 the numeral 23 to provide for the numeral 22 and in having the digit 3 of the numeral 13 associated with the digit 1 of the numeral 14 to provide the numeral 31.

In Fig. 5, is shown an arrangement of the 95 digits and numerals for setting to successive days by left hand or counter clockwise rotation. With this arrangement the transpositions required in the case of clockwise rotation are eliminated.

100 For convenient setting of the week-day disk, the week-days should read the opposite way around from the month-days, the week-day disk of Fig. 4 being used with the month-day disk of Fig. 3, and the week-day disk of Fig. 6 being used with the month-day disk of Fig. 5. However, owing to the fact that the designations on one of the two associated disks is read above the center and the other below the center, the 110 direction of rotation of both disks in consecutive setting is the same.

The foregoing detailed description has been given for clearness of understanding and no undue limitation should be deduced therefrom, but the appended claims should be construed as broadly as permissible in view of the prior art.

What I claim as new, and desire to secure by Letters Patent of the United States, is

- 10 1. The combination of a month-day disk bearing digits for representing the days of the month, the digits being in such sequence and with such spacing that one set of digits for representing the month days from 1 to 9 inclusive also will form parts of two digit month-day designations, a cover having an opening through which two consecutive digits may be seen, and means for setting the disk, substantially as described.
- 15 2. The combination of a month-day disk

bearing digits for representing the days of the month, the digits being in such sequence and with such spacing that one set of digits for representing the month-days from 1 to 9 inclusive also will form parts of two digit month-day designations, and having the digit 1 associated with the numeral 12 to provide for the numeral 11, and having the digit 2 associated with the numeral 23 to provide for the numeral 22, and having the digit 3 of the numeral 13 associated with the digit 1 of the numeral 14 to provide the numeral 31, a cover having an opening through which two consecutive digits may be seen, and means for setting the disk, substantially as described.

Signed at New York, New York, this 25th day of July, 1916.

ALTHEA MILLER.
